UNITED STATES PATENT OFFICE.

ALEXANDER SICILIANO, JR., OF LONDON, ENGLAND.

APPARATUS FOR FEEDING WATER TO BOILERS UNDER PRESSURE.

Application filed June 26, 1922. Serial No. 571,025.

To all whom it may concern:

Be it known that I, ALEXANDER SICILIANO, Jr., C. E., of Broad Street House, New Broad Street, London, E. C. 2, England, 5 Brazilian subject, have invented certain new and useful Improvements in and Connected with apparatus for Feeding Water to Boilers Under Pressure, of which the following is a specification.

10 My invention relates to improvements in and connected with apparatus for feeding water to boilers under pressure, of the kind wherein the feed inlet valve is actuated or controlled by the movement of a hollow vessel which is mounted on a counterweighted lever and in communication with the interior of the boiler through a chamber or connection mounted upon the boiler front.

According to my invention, the apparatus 20 consists in a hollow vessel mounted on a counterweighted lever and connected to the boiler by a tubular pivotal connection which at one end is connected with an opening to the boiler at the normal level of the 25 water in the boiler and which may actuate the feed inlet directly or through apparatus which on being controlled by the movement of the aforesaid lever, is capable of delivering water to the boiler and thus restoring 30 the normal level, all as hereinafter described with reference to the drawings.

In order that my invention may be properly understood and readily carried into effect, I have hereunto appended a sheet of 35 drawings, of which

Figure 1 is an elevation of the first part of my invention.

Figure 2 is a cross section of the steam tight sleeve.

40 Figure 3 is a general arrangement illustrating my invention.

The apparatus which I make use of to carry out my improvements consists of a 45 hollow spindle A or tubular pivotal connection (Figure 2) to which is fitted a steam tight sleeve B. This sleeve B is all one casting with the counterweight arm C' and pipe B'. The latter pipe B' is connected to a hollow receptacle D at its free extremity. 50 A pipe U serves to facilitate the discharge of water from the receptacle D and its action will be described further on. N is a tap which allows all air to be expelled from the system when the apparatus is first 55 started.

When the level of the water in the boiler

is below the normal level line and is therefore below the opening of the hollow spindle A, the receptacle D is empty, and by the action of the weight C, the receptacle D 60 is raised, and the rod V is lifted and actuates a valve admitting water to the boiler. As soon as the water covers the port A' of the pivot spindle A it intercepts the direct contact from the steam in the boiler and the 65 steam in the receptacle D, the steam in the latter condenses and the water then passes in to the receptacle D. When the receptacle D is full the lever system is thrown out of balance and the receptacle D moves down- 70 wards in a clockwise direction as will be understood. This movement is transmitted to the rod V which actuates a valve X and closes the admission of water to the boiler. The length of rod or arm V is regulated so 75 as to keep the receptacle D when full in its horizontal position and act as a stop. As soon as the level in the boiler O begins to fall and the port A' of spindle A is un- 80 covered, the water in the receptacle D begins to flow back by gravity into the steam generator and the system again resumes its original position, namely upwardly inclined. It is forced to do so because the counter- 85 weight C is adjusted so as to effect this.

Figure 2 shows in detail the pivot spindle A, sleeve B, and pipe B'. An opening or recess M is cut in the side of this pipe B', as shown, in such a position as to enable the receptacle D to be in direct communication 90 with the boiler O at any position of the lever system. The pipe U forms a duct which serves to carry steam to the receptacle D in connection with the clearance slot or opening M and thus facilitates the outward flow 95 from D.

The secondary part of the invention is intended to work in conjunction with the device described above and is based upon the principle of communicating tanks. 100

A pipe W (Figure 3) connects the upper part of the boiler O through valve X controlled by the rod V (Figure 1) with the vessel H, which however, must be higher than the level of the water in the boiler O. 105 The vessel H is connected with the water supply by pipe K', fitted with a check valve K. Vessel H is connected with the bottom of the boiler O by pipe J' fitted with a check valve K². 110

The apparatus works as follows:—
Supposing the boiler O is empty, it is

- filled with water in the usual way. Valve X is in the closed position and the boiler O is put under pressure. As soon as feeding is needed the automatic apparatus shown in 5 Figure 1 will move upwards for reasons already explained and thus opens valve X through the means of the control rod V. Steam from the boiler O enters vessel H through pipe W and puts it under pressure. 10 Water now flows from the vessel H through the pipe J' until the water level in the boiler O is restored. At this moment water enters the receptacle D and moves the lever system downwards, thus causing the valve X to be 15 closed and shutting off steam to container H. The steam in the container H condenses and draws water through check valve K and fills same. Water feeding to boiler thus automatically stops.
- 20 This cycle of operation repeats itself automatically whenever the water level in the boiler O lowers below that of the port A' in the controlling apparatus.

Claim:

- 25 In combination, a steam boiler, a water

feed vessel arranged at a higher point than the normal water level in the boiler, a feed water pipe connected to said vessel and having a check valve, a water pipe leading from said vessel to the boiler and also having a 30 check valve, a steam pipe connecting the vessel and the boiler, a valve in said steam pipe; a lever having a duct, a pivotal connection between the lever and the boiler and including a duct in communication with 35 the duct of said lever, and open at all times for the passage of steam or water to a connection between the lever and said steam valve, to cause the latter to be operated by the lever, and a receptacle and a counter-weight carried by the lever, the said duct of the lever leading to said receptacle.

In testimony whereof I affix my signature in presence of two witnesses.

ALEXANDER SICILIANO, JUNIOR.
